W. T. MUNGER, OF BRANFORD, ASSIGNOR TO P. AND F. CORBIN,
OF NEW BRITAIN, CONNECTICUT.

Letters Patent No. 85,754, dated January 12, 1869.

IMPROVEMENT IN REVERSIBLE LATCHES.

The Schedule referred to in these Letters Patent and making part of the same.

To all whom it may concern:

Be it known that I, W. T. MUNGER, of Branford, in the county of New Haven, and State of Connecticut, have invented, made, and applied to use a certain new and useful Improvement in Locks; and I do hereby declare the following to be a full, clear, and exact description of the same, reference being had to the annexed drawing, making part of this specification, wherein—

Figure 1 is an elevation of the lock, with a portion of the cap-plate removed, to show the interior;

Figure 2 is a vertical section at the line $\dot{x} x$, fig. 1;

Figure 3 is a partial horizontal section through the lock-case and sliding plate; and

Figure 4 is an elevation of the sliding plate behind a portion of the cap-plate.

Similar marks of reference denote the same parts.

This invention relates to a reversible latch in a lock, and consists in a slide for holding the shank of the latch to its position in the swinging link, in combination with a projection upon said swinging link that operates the said holding slide, so that the simple act of pressing in the latch, after it has been reversed, or the turning of the handle to draw in said latch, secures the latch in position, so that it cannot be reversed again until the slide is drawn back.

By this construction, the parts that retain the latch in position can be operated after the lock has been put in place in the door, thus avoiding the necessity of taking out a lock from its mortise if the slide has not been previously moved, and returning the slide to position if displaced by a jar or otherwise.

In the drawing—

a represents the box of the lock;

b, the cap-plate; and

c, the face-plate, through which the head *d* of the latch slides as usual.

e is the shank of the latch, with a head, 1, setting within a cavity in the swinging link *f*.

2 is the centre stud for said link *f*.

3 and 4 are studs for the arm *g* of the hub *h* to act upon, and withdraw the latch by the hub *h* being turned by the knob and spindle of the door.

The shank *e* is guided in the projecting flange *5*, and the head *1* may be drawn out of the cavity in *f*, and drawn forward, so as to allow the square base of the latch to be outside of the plate *c*, and be reversed; but, when the slide-plate *k* intervenes between the cap-plate *b* and shank *e*, the latch *d* *e* is held firmly in its position.

The slide-plate *k* is fitted with a thumb-piece, 6, coming through and sliding as a dovetail in the bevelled-sided slot in the cap-plate *b*, so as to retain the same in position, the upper end of the slot in the plate *b* being wider, as seen in fig. 4, to allow this thumb-piece 6 to be inserted.

The stud 13 projects above the upper end of the slide *k*, as seen in figs. 1 and 2, so that the plate *k* can be slid up into the position shown in fig. 1 by red lines, for allowing the latch to be reversed; but as soon as the link *f* is moved by the latch *e* being pushed in, or the knob and hub *h* turned, the stud 13, pushing down the slide-plate *k*, places the same in the position shown in fig. 2, to hold the button-end of the shank in its cavity in the swinging link *f*.

I do not claim a reversible latch in which a spring-catch, connected with the slide, is employed to hold the shank of the latch when inserted.

What I claim, and desire to secure by Letters Patent, is—

The slide *k*, or its equivalent, that is moved to hold the latch in position when the parts that intervene between the latch and spindle are themselves moved, substantially as set forth.

In witness whereof, I have hereunto set my signature, this 11th day of August, A. D. 1868.

W. T. MUNGER.
